US0D1113891S

(12) **United States Design Patent** (10) **Patent No.:** **US D1,113,891 S**
(45) **Date of Patent:** **** Feb. 17, 2026**

(54) **MULTIPLE DWELLING UNIT ROUTER**

(71) Applicant: **Charter Communications Operating, LLC**, St. Louis, MO (US)

(72) Inventors: **Chelsea Young**, Englewood, CO (US); **Ethan Miller**, Parker, CO (US); **Ian Ruppert**, Denver, CO (US); **Samuel Ach**, Aurora, CO (US)

(73) Assignee: **Charter Communications Operating, LLC**, St. Louis, MO (US)

(**) Term: **15 Years**

(21) Appl. No.: **29/905,047**

(22) Filed: **Oct. 16, 2023**

(51) LOC (15) Cl. **14-03**

(52) U.S. Cl. **D14/240**
USPC ....

CLAIM

The ornamental design for a multiple dwelling unit router as shown and described.

DESCRIPTION

FIG. 1 is a front-top perspective view of the multiple dwelling unit router.

FIG. 2 is a front-bottom perspective view of the multiple dwelling unit router.

FIG. 3 is a back perspective view of the multiple dwelling unit router.

FIG. 4 is a front view of the multiple dwelling unit router.

FIG. 5 is a back view of the multiple dwelling unit router.

FIG. 6 is a left view of the multiple dwelling unit router.

FIG. 7 is a right view of the multiple dwelling unit router.

FIG. 8 is a top view of the multiple dwelling unit router; and,

FIG. 9 is a bottom view of the multiple dwelling unit router.

The broken lines shown in FIGS. 1-9 represent portions of the multiple dwelling unit router that form no part of the claim.

1 Claim, 7 Drawing Sheets
